UNITED STATES PATENT OFFICE.

LAWRENCE L. NEEBE, OF WOODBURY, NEW JERSEY.

LOCOMOTIVE FIRE BOX.

Application filed October 23, 1926. Serial No. 143,777.

My invention relates to certain improvements in the fire-box section of a boiler of the locomotive type, in which there is a foundation-ring, overhead drums, and water tubes connecting the drums with the foundation-ring.

One object of my invention is to improve the construction of this type of boiler, so that it will withstand the strains to which it is subjected.

Another object of the invention is to relieve the water tubes of any duty as supports for the drums, by providing cover and supporting plates which connect the drums with the foundation-ring.

A further object is to locate a saddle directly in front of the back tube-sheet of the boiler which acts as a waist-support and also as a support for the foundation-ring, relieving the cover-plates of horizontal stresses.

And a still further object is to relieve the back tube-sheet from horizontal stresses caused by pressure on the back-heads of the drums.

The invention relates also to certain details of construction referred to hereinafter.

In the accompanying drawings:

Figs. 1^a and 1^b are longitudinal sectional views of a locomotive boiler illustrating my invention;

Fig. 2 is a transverse sectional view on the line 2—2, Fig. 1^a;

Fig. 3 is a transverse sectional view on the line 3—3, Fig. 1^a;

Fig. 4 is a sectional plan view on the line 4—4, Fig. 1^a;

Fig. 5 is a sectional view on the line 5—5, Fig. 1^b;

Fig. 6 is a detached sectional view showing the method of attaching the rods to the front tube sheet;

Figs. 7 and 8 are detached views of the saddle; and

Fig. 9 is a detached perspective view illustrating the forward end of one of the drums.

The boiler 1 is of the tubular type having a front tube-sheet 2 and a rear tube-sheet 3, to which the horizontal flues 4 are attached. The fire-box 5 is at the rear end of the boiler and the smoke-box 6 is at the front end.

The foundation-ring 7 extends the full length of the fire-box and has two longitudinal side members 8—8^a, end member 9—9^a, a central longitudinal member 10, and a cross-member 11.

The particular construction of this foundation-ring is fully set forth and claimed in an application filed by me on the 29th day of January, 1926, Serial No. 84,661.

The rear tube sheet 3 has two openings, and surrounding each opening is a flange 12 which projects into the fire-box. Drums 13 extend through the openings in the rear tube-sheet and in the rear plate 14 of the fire-box. This plate is flanged at 15 around the opening. Each drum is riveted to the flange 12 of the rear tube sheet 3 and also riveted to the flange 15 of the rear plate 14. Each drum extends a considerable distance 70 into the boiler 1 as shown in Fig. 1^a.

Each drum is flattened at the forward end to fit the contour of the inclined upper portion of the wagon top boiler and is riveted thereto by a series of rivets, Fig. 3. By 75 using the wagon top type of boiler, the drums can be properly located without materially diminishing the number of tubes in the boiler, and the drums are properly located in relation to the steam space of the 80 boiler. The shape of the flattened portions is clearly shown at 13^a in Figs. 3 and 9. Within each drum at its forward end is a cross-bar 18 firmly riveted to the drum as shown in Fig. 2, and coupled to this bar 85 by bolts 19 are three rods in the present instance which extend to and through the front tube sheet 2 of the boiler, as clearly shown in Fig. 1^b. The three rods are on the same plane, as shown in Fig. 5, so as not 90 to interfere with the tubes of the boiler or the space in the upper portion of the boiler above the rods. The rear end of each drum is closed by a head 16. The rivets, together with the rods 17 which extend to 95 the front tube-sheet shown in Fig. 1^b, resist any strains due to pressure on the closed rear ends of the drums. The two drums are tied together by spacers 36 within the boiler. By extending the drums within the boiler, and 100 by securely fastening the forward ends of the two drums to the boiler shell, the rear plate of the fire-box is relieved from downward pressure.

The two sets of rods 17 are supported midway of their ends by cross-bars 20, Fig. 5, and the rods are held onto the cross-bars by U-shaped clamp members 21. The ends of the rods extend through the tube-sheet 2 which is beveled as shown in Fig. 6, and on 110 each side of the sheet are beveled washers 22. Adapted to the threads of the rods are

nuts 23, which clamp the washers firmly to the tube-sheet.

In front of the foundation frame 7 is a cast steel saddle 24, shaped as shown in Figs. 5 7 and 8. This saddle acts as a waist-sheet support and as a support for the foundation frame, both vertically and horizontally. In supporting the frame horizontally, it holds the frame against the action of the 10 boiler pressure on the back of the frame, which tends to pull the frame away from the boiler proper. The anchorage also leaves the side cover plates free of stress, thus allowing the cover plates to act only as 15 vertical supports for the drums.

The openings in the foundation frame for the tubes are staggered as shown in Fig. 4. The tubes 25 extend from the side members 8-8^a of the foundation frame to the drums 20 13, and the tubes are preferably staggered as shown in Fig. 4, so that a greater number of tubes can be arranged on each side of the fire-box than heretofore. The tubes are reduced in diameter where they connect with 25 the frame.

The cross-member 11 is connected to the drums 13 by tubes 26. These tubes are bent as shown in Fig. 1^a and support the bricks 27 which form part of the bridge-wall 28, 30 the main portion of which is located directly back of the tubes 26. By this arrangement, the products of combustion are deflected towards the drums before passing to the combustion chamber and through the main tubes 35 of the boiler. The combustion chamber is between the rear tube sheet 3 of the boiler and the bridge-wall 28 and is of sufficient depth as to prevent the flames striking the rear tube-sheet.

40 Extending from each outer edge of the foundation frame are plates 29. These plates 29 are attached to the frame and to brackets 30 on the drums 13. The plates support the drums between the front and rear of the fire-box, relieving the water tubes of any duty as supports, thereby reducing to a minimum the tendency of the tubes to leak at the connections to the drums and the foundation frame. These plates also hold 45 the fire-brick lining in place.

The back-plate 14 is rigid and is a permanent part of the fire-box. The side plates, however, are made removable so as to facilitate repairs on the fire-bricks and tubes. 55 Between the plates 29 and the outer row of tubes 25 is a fire-brick wall 32. The lower portion of the fire-brick wall embeds both sets of tubes for a distance equivalent to the depth of the fire, but the major portion of the wall is tangent to the outer row of tubes, leaving both rows of tubes exposed to the direct heat of the products of combustion.

60 There is a double row of fire-bricks 38 between the drums 13-13 which confines the

fire to the water side of the drums. The 65 bricks of one row are slightly beveled on one side as shown in Fig. 2, so that when a brick of one row is placed, a brick of the other row can be inserted between the first-mentioned brick and the drum. At each 70 front corner of the foundation-ring are tubular extensions 33, which are coupled by flanged angle pipes 34 to the flanged tubular members 35 opening into the boiler, so that the circulation of water is maintained 75 throughout the boiler and the fire-box structure. By this arrangement, the boiler is connected directly with the hollow side members of the foundation-ring. The space between the two tubular members 35 of the 80 boiler forms a mud space. In the bottom of the boiler is a wash-out opening closed by a plug 39.

On the outside of the plates 29 and the drums 13 is a suitable lagging or other suitable covering 37, which retains the heat 85 within the fire-box.

By the above construction, all stay-bolts are dispensed with and the tubes which connect the foundation frame to the drums are 90 not subjected to strains, as the plates relieve the tubes of the strains, and all pressure on the rear of the drum is resisted by the rods, which are connected to the front tube-sheet and by rivets connecting the drums to the 95 shell of the boiler.

I claim:—

1. The combination in a boiler of the locomotive type, of a shell; front and rear tube-sheets; tubes connecting the sheets; a 100 fire-box at the rear of the boiler proper; a foundation-ring at the base of the fire-box; two drums extending from the rear tube-sheet and over the foundation-ring, the drums extending some distance into the 105 boiler proper; a cross-bar at the front end of each drum; a series of rods all on the same plane and attached to the cross-bars, said rods extending through and secured to the front tube-sheet; and means for securing 110 the front end of each drum to the shell of the boiler.

2. The combination in a boiler of the locomotive type, of a boiler proper having a fire-box at one end; a foundation-ring at 115 the base of the fire-box; two drums extending from the sides of the foundation-ring to the drums, said foundation-ring having a transverse section some distance from the front thereof; a bridge-wall mounted on the transverse section; a series of tubes connected to the transverse section and extending diagonally towards the rear of the fire-box and coupled to the drums; 120 and deflecting brick-work mounted on the tubes at the rear of the bridge-wall for deflecting the flame in the fire-box. 125

3. The combination in a boiler of the locomotive type, of a shell; front and rear tube-sheets and tubes; a fire-box structure; drums extending through the rear tube-sheet of the boiler and supported by the rear plate of the fire-box, said drums having flattened portions in contact with the shell of the boiler; and means for securing these flattened portions to the shell. 25
- 6 4. The combination in a boiler of the locomotive type, of a shell; front and rear tube-sheets; a fire-box structure consisting of a foundation-ring, two drums located side by side and extending through the rear tube sheet of the boiler and the rear tube-sheet of the fire-box and secured thereto, said drums extending a considerable distance into the boiler and having flattened portions which conform to the shape of the shell of the boiler, said flattened portions of the drum being secured to the shell of the boiler, a spacing member located between the two drums at a point near their forward end, 15 20 40
5. The combination in a boiler of the locomotive type, of a shell; front and rear tube-sheets; a fire-box at the rear of the boiler having a hollow foundation-ring; a plate forming the rear end of the fire-box; two drums extending through the rear tube sheet of the boiler and through the rear plate of the fire-box, the rear ends of the drums being closed, the front ends communicating with the interior of the boiler, the drums extending a considerable distance into the boiler, the shell of the boiler being tapered, the drums being flattened to conform to the taper; rivets securing the flattened portions of the drums to the tapered portion of the boiler; rods extending from the drums to the forward tube-sheet; and intermediate supports for the rods, said supports being secured to the shell of the boiler. 30 35
